UNITED STATES PATENT OFFICE.

EDMUND P. KINNE, OF ALLIANCE, OHIO, ASSIGNOR TO AMERICAN STEEL FOUNDRIES, OF CHICAGO, ILLINOIS, A CORPORATION OF NEW JERSEY.

COUPLING-KNUCKLE STOP.

1,106,458.

Specification of Letters Patent. Patented Aug. 11, 1914.

Application filed April 1, 1914. Serial No. 828,791.

To all whom it may concern:

Be it known that I, EDMUND P. KINNE, a citizen of the United States, and resident of Alliance, in the county of Stark and State 5 of Ohio, have invented certain new and useful Improvements in Coupler-Knuckle Stops, of which the following is a specification.

My invention relates to car couplers and 10 has particular reference to a novel motion-limiting stop associated therewith.

In the operation of railway car couplers it is customary to provide stops which shall 15 limit the movement of the coupler knuckle both in opening and closing. The stop usually employed for limiting the opening movement of the knuckle is a lug cast on either the top or bottom of the knuckle tail, said lug being adapted to co-operate with 20 a front wall of the coupler head. Experience has proven, however, that such stops are easily broken even though constructed of as large size as is possible in view of the restricted space. The strains to which such 25 stops are subjected are usually concussive and inasmuch as such blows are applied many hundreds of times in the life of a coupler, the breakage is not surprising.

I have conceived the idea of providing a 30 stop so arranged as to distribute the strain over a larger surface and to change the strain from shear to compression. Thereby the forces are taken up with less tendency to breakage inasmuch as the material from 35 which the devices are constructed has a much greater compressive strength than shear strength and the strain is distributed over a greater area.

My invention will be more readily understood 40 by reference to the accompanying drawings, wherein,

Figure 1 is a plan view of a coupler knuckle having my improvement applied thereto, the knuckle being mounted in a coupler head which is shown in section, and, 45 Fig. 2 is a section on the line 2-2 of Fig. 1.

Referring more particularly to the drawings it will be seen that my improvement is applied to a car coupler having a head 10, 50 provided with a front wall 11, through which an opening is made for the passage of a knuckle tail 12, the knuckle being mounted on a suitable pivot 13, and adapted for os-

cillation within the head. On the lower face of the knuckle tail I provide a lug 14, having a beveled face 15, and adapted to co-operate with a similarly inclined surface 16, on the wall 11, said inclined surface forming the lower portion of the opening through which the knuckle tail extends. The upper 55 surface of the knuckle tail moves in close proximity to the horizontal surface 17, which bounds the opening through the wall 11, at the top. It will be seen that as the knuckle is opened, the surfaces 15, 16, are 60 brought into contact and the knuckle is forced upwardly into contact with the surface 17. Thus a portion of the strain is transmitted to the upper portion of the wall 11 and the tendency to breakage of the lug 65 14, is considerably reduced. Preferably the angle of inclination of the surfaces 15, 16, will be such as to obviate the possibility of wedging.

A construction such as described has been 70 found to be efficient in service, removes the possibility of breakage of the opening stop and involves no added expense in the construction of the coupler.

I claim:

1. In a car coupler, the combination of a 75 head having a front wall with an opening therethrough, and a knuckle having a tail provided with a motion-limiting stop, said tail being adapted for passage through the 80 opening in said front wall, said stop being constructed to wedge said knuckle tail against the upper and lower bounding edges of the opening in said front wall, substantially as described.

2. In a car coupler, the combination of a 85 head having a front wall with an opening therethrough, one edge of said opening being beveled, and a knuckle having a beveled motion-limiting stop; the beveled surfaces on 90 said stop and said wall being adapted for co-operation whereby to force said knuckle against an opposite edge of said opening, substantially as described.

Signed at Alliance, Ohio, this 26th day of 100 March 1914.

EDMUND P. KINNE.
